UNITED STATES PATENT OFFICE.

MIGUEL BUKOVECZ, OF MEXICO, MEXICO.

INSTANTANEOUS SAFETY-SWITCH.

1,349,184.

Specification of Letters Patent. Patented Aug. 10, 1920.

Application filed January 25, 1919. Serial No. 273,056.

To all whom it may concern:

Be it known that I, MIGUEL BUKOVECZ, of Jugo-Slav nationality, residing at Mexico city, Federal District, Mexico, have invented certain new and useful Improvements in Instantaneous Safety-Switches, of which the following is a specification.

This invention relates to instantaneous safety switches for both direct and alternating currents, as well as for multiple-way selective circuit closing.

One of the objects is to provide a switch construction inclosed in a casing, which will avoid all danger of accidents by touching the fuses or exterior parts of the switch, as well as any tampering whereby fraud could be committed without leaving visible signs. The fuses are made of a simple but new construction, and access to them is only possible when the switch is thrown to the opposite extreme position, in which it leaves no current to the accessible fuses. The invention also enables connection to either one of the two motors, the lines of which join in the switch, but receive current one at a time, selectively.

Another object is to provide means for reversing the current through the lines connected to a motor, with the object of revolving it in the opposite direction.

Figure 1 is a perspective view of a double pole instantaneous switch, with fuses.

Fig. 2 is an enlarged perspective view of the same, parts being broken away to show the inside.

Fig. 3 is a perspective view of the casing inclosing a reversible switch with adjustable bar.

Fig. 4 is a perspective view of one of the contact bridge pieces.

Fig. 5 is a plan view of the said contact bridge pieces assembled, forming the contact carriage.

Fig. 6 is a perspective view of a three pole reversible switch with locking device for interchanging two motors.

Fig. 7 is a plan view of the construction shown in Fig. 6.

Fig. 8 is a plan view of the insulating plate for the reversible switch shown in Fig. 3.

Fig. 9 is a cross section of the contact screw and fuses.

Fig. 10 is a cross section of a contact knife as used in all the switches.

Referring to Figs. 1 and 2, which show

a safety switch for a common two pole connection, (1) is a wooden board to which the casing (2) is fastened by means of angle brackets (3) and wing screws (4), which should of course be properly sealed to the board. The upper side edges (5) of the casing are folded over so as to guide the sliding cover (6), to which the insulating pieces (7) are attached, between which the contact bridge pieces (8) are fitted and held thereby in position, (Fig. 5). These bridge pieces (8) have insulating strips (9) attached to the middle portion thereof, and both ends, marked (10), are bent outwardly so as to facilitate the insertion of a contact knife between two oppositely disposed bridge pieces. Springs (11) are inserted between the insulating pieces (7) and the bridge pieces (8), so as to force them together and make a good contact with the knives (12) and (13), projecting from the insulating base (14), which is raised from the board (1) by the feet (15). The contact knives are electrically connected to the contact screws (16), on which the wires (17) are fastened, as usual, by the nut and washer (18) and (19).

The insulating base (14) has a partition (20) of insulating material which will avoid tampering. The current passes through the contact plate (21) from the knives (12) to the contact screws (22), and then over the fuses (23) to the contact screws (24), to which the wires (25) are fastened. As will be seen in Fig. 9, the fuses are clamped between upper and lower contact jaw pieces (26) and (27), forced together by the nuts (28) against the spiral springs (29), surrounding the contact screws (24) which pierces the base (14). The wires (25) are retained between washers (30) and (31) by the nut (32).

A hinged lid (33) gives access to the fuses, but only when the slidable cover (6) has been carried to the position shown in Fig. 2, in which position no current can pass from the wires (17). In Fig. 1, the slidable cover (6) is slid to the contact position, and the switch handle (34), the legs (35) of which turn in the brackets (3), has been thrown over the hinged lid (33) so that the spiral spring (36) has pulled the cover (6) partly over the lid, whereby it prevents the lid from being opened.

The function of this apparatus is easily understood after the foregoing description,

keeping in mind that the contact knives are stationary, while the contact bridge pieces are fastened to the cover, and therefore move toward and away from the knives, like a carriage.

The operation of switching on is instantaneous, due to the spring which draws the cover over, when the handle (34) is swung over to either end of the casing.

- 10 In Figs. 3 and 8, I have shown a reversible safety switch of two poles; the wires (37) conducting current to the middle contact screws (38), and the cross wires (39) connecting the end contact screws (40) and (41), while the wires (42), which are also connected to the contact screws (41), lead to a motor adapted for reversed current. All these contact screws (38), (40) and (41) are electrically connected to their corresponding contact knives, shown in dotted lines in Fig. 8, projecting on the opposite side of the insulating base (43), the bottom of which is shown in Fig. 8, and being contained in the casing (44), (Fig. 3).
- 15 The slideable cover (45) of this switch is operated by the lever (46) which extends across the top of the casing (44) and moves over the in-turned upper edges (44') thereof. The lever is thrown to one of the extreme positions, one of which is shown in dotted lines, as well as the intermediate position. When the lever (46) is brought to the intermediate position, in which it falls into a notch (44²) formed centrally of one of said edges or flanges (44'), no current can pass because the bridge pieces, as shown in Fig. 5 do not connect any set of contact knives, and furthermore the insulating strips (9) of the bridge pieces (8) embrace the contact knives electrically connected to the contact screws (38). Now, supposing that the lever (46) were brought to the extreme position at the right of Fig. 8, then the contact bridge pieces would connect the contact knives corresponding to the contact screws (38) and (40), and in the same manner, if the lever (46) were brought to the left, then the contact bridge pieces would connect the contact knives corresponding to the contact screws (38) and (41), whereby the current would be reversed, due to the disposition of the cross wires (39).

20 In Figs. 6 and 7, I have shown how the invention is applied to a three pole selecting switch. The casing (47) is provided with two hinged lids (48) and (49), and an intermediate slideable cover (50), which will always obstruct the opening of either of the lids. The handle (51) is fulcrumed in 25 the arched supports (52), fixed to the sides of the casing (47) while the coil springs (53) will produce tension between the handle and the cover. Three pairs of contact bridge pieces (8) and their coöperating elements, like those illustrated in Figs. 4 and

5, are attached to the inside of the cover, in order to move therewith to any of the three positions, either of the two extreme positions or to the middle position, which is the neutral position, while the extreme positions 70 will allow the current to flow from the intermediate contact knives (54) to the contact knives (55), at the right of Fig. 6, or to the contact knives (56) disposed at the left, or opposite end of the switch. In order to 75 make the switch instantaneous in its operation, a latch bar (57) provided with bent ends (58) slides in the supports (59), fastened on top of the slideable cover (50), and also slides in the sleeve (60) fixed to said 80 cover. A projecting pin (61) on the latch bar is adapted to enter into either of the two notches (62) of said sleeve (60). In Fig. 6, the switch lies at the right-hand end between the wires (63) and the three wires 85 (64); and should it be desired to reverse the switch so as to give current to the wires (65) on the opposite end and leading to another motor, then the bar is turned upward through a quarter revolution so as to 90 disengage pin (61) from the left-hand notch (62) and at the same time to aline its bent right-hand end with the cross-groove (66) in a stop block (67) on the right-hand cover (49). Thereafter, the bar is turned back 95 to its former position, engaging pin (61) in the right-hand notch and catching its right-hand end in stops (67), whereby the bar is retained in position. After this operation, the handle (51) may now be swung 100 over toward the wires (65), thereby giving tension to the springs (53), and by disengaging the projecting pin (61) from the notch (62) and the bar end from the stop (67), the latch bar is released like a trigger, 105 and springs to the left, moving the cover (50) in the same direction until its left-hand bent end strikes against the left-hand stop (68) which is mounted on the left-hand lid (48).

110 By this action the contact bridge pieces will have established connection between the contact knives (54) and (56), leading to the wires (65).

115 The fuses (69), like those described in Fig. 2, are separated by the insulating partition (70), and may be furthermore protected against sparks from high tension current, by means of transverse insulating partitions between each fuse, which is self-explaining.

120 Having thus described my invention what I claim is:

1. An instantaneous safety switch comprising a casing, an insulating base in said casing provided with two sets of stationary contact knives, one set connected to the main line and the other through fuses to the power receiving device, a hinged lid covering said fuses, an insulating cover adapted to 125

slide over said lid, sets of contact bridge pieces attached to the inside of said cover adapted to connect said sets of contact knives when the cover is slid over said lid, 5 said bridge pieces being covered with insulating material at their intermediate portion opposite to the contact knives, and spring means connected with the cover and adapted to be put under tension so as to automatically shift said cover alternatively in one 10 direction or the other to make or break contact between the knives and the bridge pieces.

2. An instantaneous reversible safety switch, comprising a casing, an insulating base inclosed therein, three sets of aligned stationary contact knives projecting from said base, the end sets of contact knives being diagonally cross connected, and the 15 intermediate set of knives receiving direct current, a slideable cover on the casing, and a set of contact bridge pieces attached to the inside of said cover and adapted to

move therewith so as to bridge either of the end sets of knives with the intermediate set 25 of knives.

3. An instantaneous selective safety switch comprising a casing, an insulating base therein having three projecting sets of aligned contact knives, the intermediate set 30 of knives being connected to the leading in wires, and the end sets of contact knives leading out to two power receiving devices, fuses between said extreme sets of knives and contained in said casing, a hinged lid 35 over said fuses, a cover on top of said casing slideable to position to permit only one of said lids to be opened at a time, bridge pieces on the inside of said cover adapted to connect either of the end sets of knives 40 with the intermediate set, and a spring trigger mechanism for carrying said cover toward either of said end sets of knives.

In testimony whereof I have affixed my signature.

MIGUEL BUKOVECZ.
